UNITED STATES PATENT OFFICE.

THOMAS H. KANE, OF YOUNGSTOWN, OHIO, ASSIGNOR TO TRUSCON STEEL COMPANY,
A CORPORATION OF MICHIGAN.

WIRE-MESH MACHINE.

Application filed July 3, 1922. Serial No. 572,512.

To all whom it may concern:

Be it known that THOMAS H. KANE, citizen of the United States of America, residing at Youngstown, in the county of Mahoning and State of Ohio, has invented certain new and useful Improvements in Wire-Mesh Machines, of which the following is a specification.

This invention relates to machinery for the manufacture of wire mesh, and more particularly of the type adapted for reinforcing concrete roadways, floor slabs and similar construction.

The main object of this invention is to provide a machine for making wire fabric, having feed rolls for advancing longitudinal wires in combination with a magazine for holding staples and automatically feeding these staples into a reciprocating die which actuates with an upper reciprocating die for forming a staple around a cross wire.

With this and other objects in view the invention consists in the novel arrangement and construction of parts hereinafter more fully set forth and described.

The drawings illustrate the preferred embodiment of the invention. However, it is to be understood that in adapting the same to meeting different conditions, various changes in the form and minor details of construction may be resorted to without departing from the nature of the invention, as claimed and set forth in the drawings.

Figure 1 is a top plan view of a manufactured portion of the wire mesh.

Figure 2 is a cross section taken on line 2-2 of Figure 1.

Figure 3 is a front elevation of the machine.

Figure 4 is an end elevation of the machine.

Figure 5 is a detail view partly in section showing one of a series of wiring heads.

Figure 6 is a detail view partly in section of a block carrying an upper die attached to the reciprocating slide of the press.

Figure 7 is a detail perspective view partly in section of the lower die and staple elevator.

Figure 8 is a side elevation of the upper die.

Figure 9 is an end elevation of the upper die.

Figure 10 is a detail side elevation of one of the cams used for elevating the lower dies.

Figure 11 is a detail sectional view of one of the cams taken on line 11-11 of Figure 10.

Figure 12 is a perspective view of one of the staple magazines.

Figure 13 is a detail sectional view showing one of the lower dies in a position for holding the staple for the coaction of one of the upper dies in curling the upper ends of said staple around a cross wire.

Figure 14 is a perspective view of one of the staples.

Figure 15 is a detail sectional view of one of the wiring heads showing the upper die at the bottom of the downward stroke, with the staple curled about the cross wire.

Figure 16 is a detail view partly in section showing means of raising an upper wire feed roll.

By referring to the drawings it will be seen that the machine in general comprises a double crank press of ordinary type.

By referring to Figures 5 and 6 which show a single wiring head of a series of wiring heads, it will be seen that 1 represents the stationary bed of the press, and 2 the reciprocating slide of the press. This reciprocating slide 2 may be caused to function in any ordinary way known to the art, and it is not the purpose of this invention to set up a new and improved element in reference to this portion of the machine. This reciprocating slide 2 carries a block 4 provided with a recess 5 immediately back of the upper die 3 for the clearance of a lower die 6, which will be more fully described as the description of this device proceeds.

This lower die 6, and actuating means for raising it are carried by a housing 7. The longitudinal wire 8 is shown passing through a guide 9 in the housing 7. In order to advance the longitudinal wire 8, I have provided horizontal feed rolls 10 and 11, which advance the longitudinal wire 8 at intervals. The staple magazine 12 is inserted into the housing 7 and retained in place by means of a wedge 13. The staples 14 are fed forward by pressure exerted on them by a pin 15 drawn forward through a

slot 16 by means of a weight 17 attached to the pin 15 by means of the chain or cable 18 which rides over a pulley 19.

The operation of the machine may be explained as follows:

The longitudinal wires 8 are placed between the feed rolls 10 and 11 by hand. The rolls 10 and 11 are turned by rotating a hand wheel 20 (see Figure 3). This hand wheel 20 is mounted on a shaft 21 which extends through the entire machine from end to end. The upper feed rolls 11 are mounted on short individual shafts 22 running in bearings 23, above which are springs 24 with provisions for increasing or decreasing the tension thereon. To facilitate the insertion of the longitudinal wires 8, the upper feed rolls 11 are slightly lifted; this operation is accomplished by slightly turning the shaft 25 which extends the full length of the machine, and is provided with a handle 26 for rocking it. The shaft 25 is provided with a series of notches 27 (Figure 16), into which extends one arm 28 of a series 25 of bell crank levers 29. The other arm 30 of the bell crank lever 29 extends under the bearings 23. When the shaft 25 is slightly rotated the arms 28 of the bell crank levers 29 are forced to the left, and the arms 30 upward, thus lifting the upper feed rolls 11 with their accompanying shafts and bearings.

After the longitudinal wires 8 are in place the handle 26 is again placed in the position shown in Figure 16, so that the upper feed rolls 11, and the lower feed roll 10 grip the longitudinal wires 8. A shaft 31 extends the whole length of the machine, and is supported by the housing 7. This shaft 31 is provided at one end with a lever handle 32 (see Figure 3). On the shaft 31 are mounted a series of cams 33, as shown in detail in Figure 10. One of these cams 33 is placed in each housing 7. Each cam 33 is provided with a groove 34 and a flange 35, used to actuate the movement of the lower die 6 which is detailed in Figure 7. Each lower die 6 is provided with a recess 36 with a projecting flange 37, this projecting flange 37 fitting into the groove 34 of the cam 33, so that when the cam 33 is rotated with the lower die 6 engaged therein, as shown in Figure 5, the lower die 6 will be caused to raise and lower as the shaft 31 is rocked back and forth.

Each lower die 6 (see Figures 5 and 7) is also provided with a slotted opening 38 through which the longitudinal wire 8 passes. This slotted opening 38 is elongated 60 to provide for the vertical motion of the lower die 6 without interfering with the longitudinal wire 8. The lower die 6 is further provided with a recess 39 around the slotted opening 38. This recess 39 is so formed as to fit the exterior of the staple 14.

Referring again to Figure 5 it will be seen that after the longitudinal wire 8 has been placed between the feed rolls 10 and 11, the hand wheel 20 is turned until each longitudinal wire 8 is fed through each lower die 6 a distance equal to that desired between the end of the fabric and the first cross wire 40 (see Figure 3). The lever handle 32 is then drawn forward, causing the shaft 31 to be rotated clockwise, raising the lower dies 6 into their position for holding the staples 14 for the co-action of the upper dies 3.

Meanwhile, when the lower dies 6 are in the lower position, the recesses 39 are in line with the staple magazines 12, and the pressure exerted on the line of staples 14 by the pins 15 has forced the staples 14 into the recesses 39. As the lower dies 6 are elevated by turning the cams 33 it carries the staples 14 with them, so that the staples 14 in their upper position surround the longitudinal wire 8, as shown in Figure 13. It will be noted that the staples 14 are formed with slightly curved ends 41, as shown in Figure 14 for the purpose of facilitating the curling of the staples 14 around the cross wire 40.

After the staples 14 have been raised, together with the plurality of lower dies 6, a cross wire 40 is inserted manually, as shown in Figure 13. The press is then tripped, causing the reciprocating slide 2 of the press to descend, carrying downwardly the plurality of blocks 4, with depending upper dies 3. As the depending upper dies 3 strike the staples 14 it curls the slightly curved ends 41 of the staples 14 around the cross wire 40, as shown in Figure 15. As the press shaft 42 continues to revolve, after forcing the reciprocating slide 2 down, it again raises the reciprocating slide 2, together with the upper dies 3, and stops in the upper position. The longitudinal wires 8 are now fed forward in any desired distance, corresponding to the spacing between the cross wires 40 by turning the hand wheel 20 when a new set of staples 14 are brought into position by pushing backward the lever handle 32, thus rocking the shaft 31 and bringing the lower dies 6 to their downward position when they will receive a new set of staples 14 from the staple magazines 12.

The lever handle 32 is now drawn forward again, raising the lower dies 6 to the operating position, and another cross wire 40 manually placed in position as before.

The cycle of operation is repeated until the cross wires 40 have been attached to the whole length of the horizontal wires 8.

What I claim is:

A machine for making wire fabric comprising a lower feed roll, a plurality of upper feed rolls for advancing longitudinal

wires, a plurality of lower reciprocating dies, cams for reciprocating said dies, a slotted opening in each die, a recess in each of said dies around said slotted opening, a plurality of reciprocating upper dies, a recess back of each upper die for the clearance of each lower die, staple magazines for auto-

matically feeding staples into the recess of each lower die, means for the co-action of the upper and lower dies forming ends of staples around a cross wire, substantially as described for the purpose set forth.

In testimony whereof I affix my signature.

THOMAS H. KANE.
